THERMOSTAT OR SIMILAR ARTICLE

Delmar K. Everitt, Santa Susana, and Ronald F. Chesley, Los Angeles, Calif., assignors to International Telephone and Telegraph Corporation, New York, N.Y., a corporation of Maryland

Filed July 18, 1966, Ser. No. 3,113

Term of patent 14 years

(Cl. D52—7)

FIG. 1.

FIG. 4.

FIG. 2.

FIG. 5.

FIG. 3.

FIG. 6.

FIG. 1 is a perspective view of a thermostat or similar article showing our new design;

FIG. 2 is a front elevational view of the same;

FIG. 3 is a top view of the thermostat;

FIG. 4 is a left side elevational view thereof;

FIG. 5 is a right side elevational view thereof; and

FIG. 6 is a bottom view thereof.

The dominant features of the design reside in the portions shown in full lines.

We claim:

The ornamental design for a thermostat or similar article, as shown and described.
